AUTOMATIC CONTROL DEVICE

George Herman Frank, Cicero, Ill., assignor to
Western Electric Company, Incorporated, New
York, N. Y., a corporation of New York

Application February 2, 1929. Serial No. 337,110

2 Claims. (Cl. 192—128)

This invention relates to automatic control devices, and more particularly to an automatic stopping device for strand working machines.

The principal object of the invention is to provide a simple, reliable, and durable device for automatically stopping a strand working mechanism.

One embodiment of the invention contemplates the provision of a device wherein a rod 10 operated by a tension arm carrying a wire traveling through a wire drawing machine is connected to a ported sleeve positioned intermediate two stationary pneumatic cylinders. When the wire breaks or the supply thereof becomes exhausted, 15 the tension arm and rod are actuated through a resilient member to move the ported sleeve into position to interconnect the cylinders and thus supply pneumatic pressure through a tube to another cylinder. The piston in the latter 20 cylinder is then operated to effect the stopping of the wire drawing machine by releasing a latch which holds a manually operated starting clutch lever in operative position against the compression of a spring.

25 Other features and advantages of the invention will become apparent from the following detailed description, reference being had to the accompanying drawings, wherein

Fig. 1 is a front elevational view of a wire 30 drawing machine having a control device embodying the features of the invention;

Fig. 2 is an enlarged fragmentary side elevational view partly in section, showing the control device in operative association with the 35 lever connections for operating the capstan clutch;

Fig. 3 is an enlarged vertical sectional view taken on line 3—3 of Fig. 2, and

Fig. 4 is a horizontal sectional view taken on 40 line 4—4 of Fig. 3.

Referring now to the drawings wherein like reference numerals designate similar parts throughout the several views, a compartment 10 of substantially rectangular shape is supported 45 by a framework 11. The wire drawing apparatus is mounted within the compartment 10 and comprises a horizontal shaft 15, upon which is mounted a plurality of integral capstans 16—16 of different diameters. Supported above the 50 shaft 15 are a plurality of sheaves 17—17 independently mounted upon a horizontally disposed shaft 18 suitably supported within the compartment 10. Mounted between the sheaves 17—17 and capstans 16—16 is a die block 19 which is

also suitably supported within the compartment 10.

A supply of wire to be reduced in diameter is carried by a supply stool 20 suitably mounted at the front of the machine.

In the drawing operation, the wire is guided from the supply spool over and under pulleys 25 and 26, respectively, and then over the rear sheave 17 and through the first reducing die (not shown) carried by the die block 19. The wire is then wound once around the capstan of smallest diameter after which it passes upward and over the next sheave 17 and through the next reducing die carried by the die block 19. The wire is then wound around the next capstan and then again over the next sheave 17 and through the next reducing die, etc., until it is finally drawn down to the desired diameter by the last reducing die. From the final reducing die the drawn wire passes around the capstan 16 of largest diameter and is guided by a pulley 27 mounted on a stationary arm 28 adjustably positioned on the shaft 18. From pulley 27 the wire passes over a pulley 30 carried by a tension arm 31, and thence is lead to a take-up spool 32 driven by a mechanism as fully described in Patent 1,598,397, J. N. Selvig, September 7, 1926.

The clutch mechanism for connecting the integral capstans 16—16 to and disconnecting them from a source of driving power is illustrated in Fig. 2, the clutch being shown in operative position. The clutch proper comprises an annular member 36 which is slidably keyed to a collar 37 rigidly fastened to the shaft 15 carrying the integral capstans 16—16. Interposed between the annular member 36 and a flange 38 of the collar 37 is a compression spring 40 which serves to keep a friction surface 41 of the member 36 in engagement with a friction surface 42 of a driving disk 43. This disk is rotatably mounted on the shaft 15 and is fastened to a bevel gear 44 meshing with another bevel gear 45 which is driven from a suitable source of power (not shown).

Superposed upon a horizontal flange of the 100 member 36 is a ring 46 held in a non-rotatable position by a lever 48 pivoted thereto. The upper end of this lever makes contact with a depending projection 49 of a housing 50 secured in the framework 11 and the lower end of the 105 lever engages at all times the upper arm of a bell crank 51 pivoted at 52. A reciprocable rod 56 is interposed between the underside of the horizontally disposed arm of the bell crank 51 and the end of a lever 57 which is pivotally 110

mounted at 58 in a bracket 59 secured to the framework 11. In a bifurcated end of the lever 57 is pivoted a threaded link 60 which passes through a telescopic spring housing composed of two members 61 and 62 and which has the lower end thereof pivotally connected to a foot pedal 63. The member 61 forms part of a depending bracket 67 fastened to the framework 11 and the member 62 threaded on the link 60 is adapted to telescope within the member 61 to compress a spring 68 when the link 60 is moved upwardly.

The upward movement of the link 60 is accomplished by depressing the foot pedal 63, thereby causing it to rock about its pivot 70. When the foot pedal is depressed, a laterally extending catch 71 thereon is engaged by a latch 72 pivoted at 73. This latch is held in locked engagement with the foot pedal 63 by a piston rod 77 which makes a swivel connection with the latch at 78 and which is normally controlled by a spring 79 interposed between a piston 81 and an end of a cylinder 80.

To release the latch 72, it can be manually moved to the left (Fig. 2) against the compressive force of the spring 79 or it can be controlled by pneumatically operating the piston 81. The pneumatic releasing apparatus includes a housing 85 fastened to the framework 11 and forming a cylinder 86 (Figs. 3 and 4) in which a stationary cylinder 87 is securely mounted thereto by a pin 88. A reciprocable sleeve 89, having a slot 90 for clearing the pin 88, is positioned intermediate the cylinders 86-87 and is rigidly secured through a pin 91 and a horizontal member 92 (Fig. 1) to a rod 93 which is connected to the tension arm 31 by a link 94. The tension arm when free is normally held in a raised position as indicated by the dot and dash lines, as shown in Fig. 1, by a clock-spring 95. For a more detailed description of this tensioning mechanism reference may be had to the aforementioned Patent No. 1,598,937.

It is to be noted that the cylinders 86-87 and the sleeve 89 have orifices or ports 97, 98 and 99, respectively, which are in alignment (Fig. 3) only when the tension arm 31 is in its uppermost position, as illustrated by the dot and dash lines in Fig. 1. The orifice 97 in the wall of the cylinder 86 is connected through tubing 100 to a source of compressed air (not shown), and the cylinder 87 is connected by a tube 102 to the cylinder 80. A dash pot effect is transmitted to the movement of the sleeve 89 by the use of needle valves 105-106 for controlling the rate of emission of air through the tubular vents 107-108 that may be imprisoned between the head of the sleeve 89 and the heads of the cylinders 86 and 87, respectively.

When the wire breaks or the supply thereof becomes exhausted during the operation of the wire drawing machine, the tension on the arm 31

is removed and the arm moves to its uppermost position due to the energy stored in the clock spring 95. The interconnecting link 94 moves the rod 93 and the sleeve 89 connected thereto downward, which movement aligns the orifices or ports 97, 98 and 99 and admits air under pressure from tube 100 therethrough into the tube 102 and cylinder 80 to force the piston 81 to the left against the compressive force of the spring 79. This movement of the piston 81 forces the latch 72 clear of the catch 71 to release the foot pedal 63. The compressive force of the spring 68 also moves the link 60 downward, thereby rocking the lever 57 clockwise to force the rod 56 upward. As the rod 56 moves upward, the bell crank 51 is rocked clockwise, thereby moving the lever 48 about its fulcrum at the projection 49 to force the ring 46 and driven member 36 to the right (Fig. 2) against the compression of spring 40 and thus separate the member 36 from the driving disk 43 to stop the rotation of the capstans 16-16.

Although the invention herein described and illustrated is particularly well adapted for use in connection with wire drawing machines, it will be understood that the invention is capable of many other applications and should be limited only by the scope of the appended claims.

What is claimed is:

1. In a strand working mechanism, means to move a strand through the mechanism, means to drive the strand moving means, a clutch to couple the driving means to the strand moving means, a tension arm associated with the clutch and held by the moving strand in one position to render the clutch operative and automatically movable to another position upon release of the strand pressure thereon to render the clutch inoperative, and a dash pot arrangement associated with the tension arm and having a reciprocable sleeve interposed between two cylinders for retarding the actuation of the clutch to prevent a momentary slack in the wire from causing the tension arm to render the clutch inoperative.

2. In a strand working mechanism, means to move a strand through the mechanism, means to drive the strand moving means, a clutch to couple the strand moving means and the driving means, a tension arm held by the moving strand in one position and automatically movable to another position on release of the strand pressure thereon, a fluid actuating device for releasing the clutch, and a combined fluid control valve and fluid dash pot arrangement having a reciprocable sleeve interposed between two cylinders and actuated by the tension arm for controlling the fluid actuating device and for preventing a momentary slack in the wire from causing the tension arm to render the clutch inoperative.

GEORGE HERMAN FRANK.
